ELECTRON DISCHARGE DEVICE

Adrianus Johannes Wilhelmus Marie van Overbeek, Eindhoven, Netherlands, assignor, by mesne assignments, to Radio Corporation of America, New York, N. Y., a corporation of Delaware

Application February 9, 1938, Serial No. 189,509
In the Netherlands February 13, 1937

5 Claims. (Cl. 250—27.5)

This invention relates to electron discharge devices of the space charge grid type and having a cathode, an anode and one or more intermediate electrodes amongst which there is a screening or accelerating electrode.

When using such electron discharge tubes, more particularly those discharge tubes which are utilized for the amplification of electrical oscillations, it is of great advantage that the tube 10 should have a slope which is as high as possible, that is to say that the inclination of the grid voltage-anode current characteristic should be as great as possible. With the use of a discharge tube having an accelerating electrode, that is to 15 say of a so-called accelerating grid or space charge grid tube, the maximum characteristic slope of a control grid which follows such an accelerating grid is decreased due to the fact that the electrons pass around the grid wires of the 20 accelerating grid, which results in an appreciable decrease of the slope.

It is the principal object of my invention to provide an electron discharge device of the so-called space charge grid type having improvements for increasing the transconductance characteristic of the tube.

The applicant has made a number of experiments on this subject and has found that an appreciable improvement may be obtained by utilizing an electron discharge tube made according to the present invention. Such a tube includes a cathode, an anode and one or more intermediate electrodes, one of which is an accelerating electrode, the latter being constructed in such manner that electron beams are formed which do not cross or cut each other so that at each definite point in front of a subsequent electrode there occur only electrons with a determined component of speed perpendicular to the plane of the subsequent electrode while this electrode or a following electrode is constructed in such manner that the equivalent or resultant voltage in the plane of this electrode is adapted or proportional to the above mentioned component with the result that in a very narrow range of voltages the whole of the electron stream impinges on this electrode or, if the latter is a grid-like electrode, is allowed to pass.

As the applicant has found by experiments, it is actually possible to give the slope a very high value by ensuring that with an increase of the voltage of the control grid suddenly, substantially all the electrons are allowed to pass. In order to attain this object it is not possible, how-

ever, to utilize ordinary grid constructions but first of all it is necessary to avoid having in front of the control grid a large number of electrons which move confusedly in all directions and at very different speeds while, in addition, care should be taken to ensure that the voltage in the plane of the grid is such that in a comparatively small change of voltage all the electrons are allowed to pass or are intercepted, that is to say such that the voltage in the electrode surface is adapted to the components of the speed of the electrons in a direction perpendicular to the surface of the electrode. According to the invention, the accelerating electrode is constructed to that end in such manner that the electrons are formed into a plurality of beams which do not cut each other while the beam-forming elements are arranged parallel to the cathode. According to one embodiment of the present invention, use may be made for this purpose of an electrode of solid sheet material which surrounds the cathode, and in which only a few apertures are provided which ensure that the electrons proceeding from the cathode are formed into beams. The formation of beams may also be effected, however, with the aid of constituent parts of the first grid arranged around the cathode, for example the supporting rods of this grid.

The electrons which emerge from the apertures in the accelerating electrode have, however, different speeds and according to the present invention, it is therefore necessary to construct the first electrode or, if desired, subsequent electrodes, in a manner so that actually the voltage in the plane of the first electrodes that follow the accelerating electrode is adapted if this electrode is made more positive suddenly, to permit nearly all the electrons to pass or be intercepted. According to one embodiment of the invention, this may be achieved, for example, by making, if the first electrode following after the accelerating electrode is a grid, the distance between this grid and the next electrode different at different points along the circumference of these electrodes, this distance being greatest at those points where the speed component perpendicular to the surface of the first electrode is largest. It is alternatively possible to utilize a variable grid which is wound with a large pitch at those points where the speed component of the electrons perpendicular to the grid surface is small and with a small pitch at the points where this component is larger.

The fundamental idea of the invention may be applied not only to any screen grid tube but also

to diodes, in which event the tube is constructed in such manner that the electrons emerging from an aperture in an accelerating electrode strike the anode at right angles.

- 5 The novel features which I believe to be characteristic of my invention are set forth with particularity in the appended claims, but the invention itself will best be understood by reference to the following description taken in connection with the accompanying drawing in which Figures 1, 2 and 3 show top end views of electron discharge devices made according to my invention and used in a hexode useful as a mixer, an octode useful as a converter, and a diode respectively.
- 10 Figure 4 is a top end view of another modification of my invention.

In Figure 1 is shown a tube illustrating the principle of my invention. An indirectly heated cathode 1 consists, for example, of a cylindrical cathode tube coated with emitting material and has inside a heating element not shown. The electrons proceeding from the cathode are formed into beams and pass through apertures provided in an accelerating electrode 2 in Figure 25 1 and 2' in Figure 2 into the further portion of the discharge tube. In the forms of construction shown in Figures 1 and 2 a control grid 3 (in Figure 1) and 3' (in Figure 2) is arranged between the cathode and the accelerating electrode 30 while in the tube shown in Figure 2 an electrode 4 is arranged inside the accelerating electrode 2'. In the form of construction shown in Figure 2 the electrodes 3' and 4 may jointly be utilized as the control grid and the anode of the local oscillator.

35 Referring to Figure 1 and considering only the upper half of the tube disclosed, it will be seen that the electrons are formed into a beam by means of the control grid 3 and the accelerating electrode 2. The electrons in the right half portion of the beam, due to the field resulting from the construction of the tube, have a velocity perpendicular to the surface of the screen grid 7, greater than that of any of the electrons in the beam since it is obvious that the angle of the 40 other portions of the beam at the point where they strike the screen electrode becomes increasingly greater, moving toward the left portion of the beam. This means that the component of the velocity of the electrons perpendicular to grid 45 7 in the left hand portion of the beam is less than the component of velocity of the electrons perpendicular to the screen 7 on the right hand portion of the beam. Hence it is necessary to space the control grid 6 at the right hand side so that the effective field at the surface of this electrode is greater in the negative sense than the effective field at the surface of this grid on the left hand side of the grid. With this arrangement and by proper spacing of the electrodes, it is possible to 50 produce a tube such that substantially all of the electrons are either permitted to pass through the grid or are returned with a very small change in voltage on grid 6. This results in a tube characteristic of the kind desired.

55 The electron beams emerging from the aperture in the accelerating electrode pass through the tube and finally reach, in the three examples shown, an anode 5 in Figure 1, anode 5' in Figure 2, or anode 51 in Figure 3. With the form of construction shown in Figure 1 the electrons pass on their way two grids 7 and 6 which may be utilized as a control grid and a screen grid. In order to attain the effect aimed at with the present invention, the grid 7 is mounted in such manner that 60 one side where the electrons reach the grid 6 at a

higher speed than on the other side, is remotest from the grid 6, the distance between the two grids decreasing towards the other side. Another possibility of construction is shown in Figure 2, in which the electrons pass between the accelerating electrode and the anode, successively through grids 8, 9 and 10. In order to obtain a correct distribution of electrons, the distance between the grids 8 and 9 is greater at those points where the electrons strike the grid 8 at the highest speed than at the other points of the grid 8. The electrodes are enclosed in an envelope 11.

In the form of construction according to Figure 3 a correct potential distribution is obtained again by giving the anode 5 a determined shape.

In the embodiment shown in Figure 4 the spacing between the second control grid 7' and the screen and anode does not vary but the size of the apertures in the second control grid 7' decreases in the direction in which the speed components 20 of the electrons perpendicular to the surface of the second control grid is the greatest.

In all the figures of the drawing the paths of the electrons are diagrammatically indicated by arrows.

25 While I have indicated the preferred embodiments of my invention of which I am now aware, it will be apparent that my invention is by no means limited to the exact forms illustrated or the use indicated, but that many variations may 30 be made in the particular structure used and the purpose for which it is employed without departing from the scope of my invention as set forth in the appended claims.

What I claim as new is:

35 1. An electron discharge device having a cathode for emitting electrons, a control electrode surrounding said cathode and an anode for receiving electrons from said cathode, and an accelerating electrode between said cathode and anode having apertures for forming the electrons emitted by the cathode into beams, the electrons of which have non-intersecting paths, and an auxiliary electrode between said anode and accelerating electrode the spacing between the auxiliary electrode and the anode being greatest at the place where the speed component of the electrons perpendicular to the surface of the auxiliary electrode is the greatest.

40 2. An electron discharge device having a cathode for emitting electrons and surrounded by a control grid, and an anode for receiving said electrons, and an accelerating electrode having apertures for forming the electrons from the cathode into beams which do not intersect each other, a second control grid and a screen grid between said anode and first control grid, the second control grid having varying size apertures, the wide apertures being positioned at those points of the grid where the speed component of the electrons perpendicular to the surface of the second control grid is the smallest, and at the position where the speed component of the electrons is larger the apertures are smaller.

45 3. An electron discharge device having a cathode for emitting electrons and surrounded by a control grid, and an anode for receiving said electrons, and an accelerating electrode having apertures for forming the electrons emitted by said cathode into beams, a second control grid and a screen grid between said anode and first control grid, the screen grid being spaced at a greater distance from the second control grid at those points of the second control grid where the speed component of the electrons perpendicular to the
